UNITED STATES PATENT OFFICE

2,572,997

PIPE CUTTER

Charles R. Edwards, Houston, Tex.; Frances Roberta Edwards executrix of said Charles R. Edwards, deceased

Original application May 13, 1940, Serial No. 334,947, now Patent No. 2,394,759, dated February 12, 1946. Divided and this application June 11, 1945, Serial No. 598,810

9 Claims. (Cl. 164—0.6)

1

This invention relates to new and useful improvements in means for recovering elements from well bores.

In the well art, it is well known that in the drilling and completion of wells, pipe, in one form or another, is substantially at all times extending into the well bore. During the actual drilling, the drill stem or pipe, which is made up of sections connected by coupling collars, has the drill bit mounted on its lower end and is rotatable so as to rotate the bit and perform the drilling operation. After the well is drilled in, well tubing and casing are disposed within the well bore and, of course, remain therein so long as the well is producing. The pipe extending into the well bore may separate, collapse or for other reasons, may fall downwardly in the bore to the bottom thereof; or the wall of the bore may cave in and firmly lodge the pipe, or a portion thereof, within the bore. When any of the foregoing occurs, it is necessary that the pipe be removed or "fished out" from the bore before the well operations may continue and manifestly, such removal, particularly where the pipe is firmly lodged or stuck within the bore, creates quite a problem.

It is, therefore, one object of this invention to provide an improved means for recovering and removing pipe, tubing, casing and other objects which may have become lodged, or which may have fallen downwardly, within a well bore.

A further object of the invention is to provide an improved means, which means is operable after effecting a removal of the unlodged or free portion of the pipe, and involves cutting the lodged portion of the pipe into sections by means of an outside cutter, whereby said lodged portion may be removed from the bore.

Another object of the invention is to provide an improved cutter having a positive driven feeding means operable to be released instantly, and means to drive the cutter faster toward the pipe at the beginning of the cut rather than when the cutting load increases due to a wider cut.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a view, in elevation, showing an outside pipe cutter, constructed in accordance with the invention, the surrounding casing being shown in section.

2

Fig. 2 is an enlarged, vertical sectional view of the top portion of an outside cutter, constructed in accordance with the elevation,

Fig. 3 is a continuation of Fig. 2,

5 Fig. 4 is a horizontal cross-sectional view taken on the line 9—9 of Fig. 2,

Fig. 5 is an enlarged isometrical view, showing the cutting knife,

10 Fig. 6 is a horizontal cross-sectional view taken on the line 11—11 of Fig. 3,

Fig. 7 is an enlarged isometrical view, showing the guide and holder for the cutting blade,

Fig. 8 is a horizontal cross-sectional view taken on the line 13—13 of Fig. 3,

15 Fig. 9 is a plan view of the guide buttons for the knives,

Fig. 10 is a horizontal cross-sectional view taken on the line 15—15 of Fig. 9,

20 Fig. 11 is an enlarged view, partly in elevation and partly in section, of a portion of the outside cutter, showing the knife in its retracted position,

Fig. 12 is a view similar to Fig. 11, showing how the knives move to their cutting positions.

It is pointed out that often the pipe is dropped 25 and bent into the shape of an elongated "corkscrew" or damaged so that it is impossible to use an inside cutter. In this event, there has been provided an improved outside cutter, which may be used if the stuck pipe can be washed over for even a few feet at a time. This tool is run on a string of tubing or pipe and telescopes over the stuck pipe. As can be seen, an outside cutter will be unable to go below the point at which the pipe is stuck and cut the pipe, while an inside cutter, 30 if the pipe is not bent or clogged, can go below the point at which the pipe is stuck.

An outside cutter 298 is inserted over the stuck pipe 360 (Figs. 1, 2 and 3), said pipe sliding up into the cutter and into the pipe 299 which is attached to the upper end of the outside cutter (Fig. 1). The cutter 298 is provided with a sectional housing comprising upper portion 300 which is connected to a central portion 301, which in turn is connected to a lower portion 302. The upper end 300 of said housing is internally screw-threaded so as to receive an adapter 303. The lower end of said adapter overhangs the bore 304 of the housing 300 to form a shoulder 305. The bore 304 is reduced to form an inwardly extending shoulder 306 used as a stop to limit the downward travel of a gripping means 316. Below said shoulder 306 the bore 304 is increased at 307, and below said portion 307 said bore is enlarged further to form a stop shoulder to limit the upward 35 travel of the slip seat 312. The lower end 308 of

the housing 300 is internally screw-threaded so as to receive the upper externally screw-threaded end 309 of the intermediate housing 301.

Referring now to Fig. 2, it will be seen that the bore of the housing 301 is slightly reduced and forms a shoulder 310. A plurality of thrust rings 311 rest on said shoulder and support the enlarged slip seat 312 of the mandrel 313. The mandrel 313 movably fits within the housing 301, and a clearance is provided between said mandrel and said housing. The upper enlarged end 312 is inwardly and downwardly tapered at 314 to form a slip seat which is provided with a plurality of inwardly extending keys 315. Confined between the head 312 and the shoulder 305 of the adapter 303 is a slip or gripping means 316. Said gripping means is provided with a plurality of slots 317 so as to form a plurality of upwardly-extending fingers 318 and a plurality of downwardly-extending fingers 319. Said fingers are each provided with wickers or a plurality of sharp grooves 320 on the inner surfaces thereof. These grooves, which are formed like threads, are used as a second form of release in case of a broken finger. The upper end of said gripping means is surrounded by a plurality of springs 321 which urge the fingers together. The lower fingers 319 depend upon and conform to the tapered surface 314 to move the fingers inwardly so that they may grip a pipe or the like. Obviously, when the lower end of the fingers are resting upon the keys 315, they cannot be brought together so as to grip a pipe; but, when said gripping means is rotated so that the keys 315 will enter the slots 317, the tapered portion will squeeze the fingers together and thereby grip a pipe that may be confined within said gripping means.

The mandrel 313 extends downwardly, and is provided with a plurality of annular grooves 322 on its outer surface which mate with a plurality of complementary annular grooves 323 in the inner surface of the housing 301 (see top of Fig. 3). The mandrel 313 has its lower portion vertically split for a distance; the splits extending somewhat above and also below the grooves 322 and the internal threads of the control, so as to permit radial expansion and contraction of the grooved portion of said control mandrel, thereby forming a split feed nut. The bore of the housing 301 is reduced below said grooves 323, and is externally screw-threaded at 324.

The lower inner surface of the mandrel 313 is screw-threaded at 325 opposite the grooves 322 so as to permit said radial expansion and contraction to engage and disengage these threads 325 with the threads 327 of the tubular feeding means 326. Said screw-threads are fine so as to act as feed threads. The threaded portions of the mandrel 313 are terminated near its lower end. The threads 327 of the feeding means 326 also terminate at this point, but extend upwardly to the upper end of said feeding means. Said means 326 extends through housing 301 into housing 302 and has its outer periphery enlarged at 328, and is provided with a plurality of windows or openings 329 in which there is pivoted on a pin 330 a plurality of traveling guides 331 which have their lower free end 332 tapered to fit against a stuck pipe. The housing 302 is attached by screw-threads to the lower end 324 of the housing 301 and is provided with a plurality of cutter carrier windows or

openings 333. It has its lowermost end 334 internally screw-threaded so as to receive an externally screw-threaded shoe member 335 whose bore 336 is reduced over the bore of the housing 5 302 to form a shoulder 337, which shoulder forms a spring seat. The lower end of said member may be provided with a plurality of cleaning teeth 338.

The member 326 (see Fig. 3) has a number of 10 slots formed in its lower thickened portion, forming legs that extend from a suitable distance above to down below the windows or openings 333, and are each provided with an outwardly-extending flange 339 which abuts the shoulder 15 340 of the housing 302 to limit the upward travel of said feeding means. The upper enlarged periphery 328 engages a shoulder 341 at the upper end of the housing 302. Lying against a shoulder stop on the guide 331, which is mounted in 20 the means 326, is a rectangular-shaped elongated push rod 342. One of said push rods lies in a vertical groove between each of said guides 331 and the housing 302. The upper ends of said rods bear against the shoulder on the rib 343, 25 which rib is bent inwardly so as to surround the upper curved end of the guide and so as to form a retainer at the upper end of the guide. The lowermost ends of said push rods 342 abut a retaining ring 344. Confined between the 30 retaining ring 344 and the shoulder 337 of the shoe 335, is a coil spring 345, which exerts an upward pressure on the retaining ring 344 which in turn acts upwardly on the push rods 342 and the guide shoulder 343, thereby resiliently holding said 35 guides in their retracted positions. A pair of lugs 346 (Fig. 3) is provided on the outer surface of each of said guides and engage within outwardly-extending side pockets 347 provided in the inner surface of the housing 302. Thus, 40 as said mandrel, guides, and rods are moved downwardly, the lugs will slide out of said pockets and force the dogs in toward the center of the device. Below said guides, the mandrel 326 is provided with a plurality of legs to form 45 the slots or long openings 348 which correspond in width, but are longer, and match with the side walls of the openings 333 in the housing 302. Within the openings 348 and 333 is a cutting assembly 349.

50 Pivoted within the housing 302 is a knife holder 350 which carries a cutting knife 351. Said knife holder, as shown in Fig. 5, has an outwardly tapered opening 352 in which the knife 351 lies. Said holder is provided with a plurality of set screws 353 for adjusting and holding the cutting member 351. Said holder is also provided with a plurality of openings 354 on the sides thereof for receiving a button gear 355 (see Figs. 8 and 9) which is held within said opening by a screw-threaded pin 356. The exposed surface of the button is provided with a plurality of outwardly extending fins or webs 357. It has been found preferable to have one of said buttons on each side of the holder, however any suitable number 55 may be used. The side edges of the windows or openings 348 of the member 326 are provided with a plurality of projecting fins or webs 358 which are provided with a suitable space 359 therebetween, so as to allow the webs 357 to pass therethrough. The space between the webs 357 is also large enough to allow the webs 358 to pass therethrough. When the device is assembled and is ready to run into the hole, the webs 357 and 358 are in the position shown in Fig. 8.

75 In operation, a pipe 299 is attached to the

upper end of the adapter 303 and the device lowered into the well which telescopes the pipe 360, as shown in Fig. 1. Said pipe will pass up through said tool and through the gripping means 316 to the lowermost point that the tool 298 can go, and at that point the device is slightly rotated and raised so as to remove the slips or gripping means 316 from the keys 315. Slight rotation may be necessary to remove said gripping means from said wings. The gripping means will have a frictional engagement with the pipe 360, and as the tool is pulled upwardly, the gripping means will relatively slide downwardly and engage in the tapered portion 314 of the mandrel 313 and force said gripping means inwardly, thereby firmly gripping the pipe. When this downward pressure is applied to the mandrel 313, the teeth formed by the grooves 322 will be forced inwardly within the grooves 323 of the housing 310, and the screw-threads, due to the downward pressure, will firmly engage the threads 325 of the mandrel 313 into the threads 327 of the feeding means 326. Thus, as the pipe 299 is rotated, the outer housings 300, 301 and 302 will rotate. The mandrel 313 and the slip 316 will be locked to the pipe 360 so that the same will not rotate due to the gripping means engaging the tapered portion between the keys 315.

As the housing is rotated, the threads 327 and 325 will begin to move the feeding means 326 downwardly. The lug 346 will begin to move the guides 331 inwardly, and the webs 358 will begin to move through the webs 357 of the button attached to the holder 350, and thereby move said holder inwardly, obviously carrying the knife 351 therewith. The spring 345 will be compressed after the cutting operation is completed, at which time the pipe 299 will turn easier to advise the operator that the cut is complete and will be in the position shown in Fig. 12. The upper tapered portion 361 of the holder will contact the pipe 360 as the cut is being completed so as to help keep the same in alignment. The dogs 331 will also slidably engage the pipe so that it will be held firmly in place, while the cut is being made, and will act to center said pipe with the tool.

In the event the operator desires to stop cutting at any time during the operation, he may slack off and release his gripping means by bringing the offsets in the slips down on the keys 315 which will permit the gripping means to spread and thereby relieve the down pressure on the mandrel 313 and which will allow the teeth 322 to spring back into the grooves 323 and disengage the threads; and the spring 345 will move the member 326 upwardly, thereby retracting the holder and knife and allowing the guides 331 to spring back into their retracted positions, as is shown in Fig. 3. Thus it can be seen that the cut may be stopped at any point, and also that a tension is held upon said pipe at all times.

Often, when the cutting of the pipe is almost completed, the pipe will twist and possibly be wedged, within many of the old type cutters, so that it cannot be retracted. Also, in many cases where the old-type cutters are used, the cut cannot be finished. The guides 331 and the tapered portion 361 of the holders 350 hold said pipe so that it cannot twist, and therefore the cut can be finished as desired.

Various changes, alterations and modifications may be made in the herein described elements,

as to size, shape and arrangement, within the scope of the appended claims.

This application is a division of my co-pending application, Serial No. 334,947, filed May 13, 1940, for Methods and Means for Recovering Elements From Well Bores, now Patent No. 2,394,759, issued February 12, 1946.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. An outside pipe cutting tool comprising an outer housing, a pipe gripping means releasably interlocked with an upper mandrel, a lower mandrel mounted within said housing said upper mandrel being connected to said lower mandrel by a releasable screw-threaded connection, cutter members pivoted to said housing and operable upon axial movement of said lower mandrel with respect to said housing, said axial movement being caused by rotary movement of the housing when the gripping means and upper mandrel are interlocked.

2. An outside pipe cutting tool comprising an outer housing, a pipe gripping means releasably interlocked with an upper mandrel, a lower mandrel mounted within said housing said upper mandrel being connected to said lower mandrel by a releasable screw-threaded connection, cutter members pivoted to said housing and operable upon axial movement of said lower mandrel with respect to said housing, said pipe gripping means being slidably mounted in said housing and comprising a cylinder having axially spaced sets of gripping teeth, said axial movement being caused by rotary movement of the housing when the gripping means and upper mandrel are interlocked.

3. An outside pipe cutting tool comprising an outer housing, a pipe gripping means releasably interlocked with an upper mandrel, a lower mandrel mounted within said housing said upper mandrel being connected to said lower mandrel by a releasable screw-threaded connection, cutter members pivoted to said housing and operable upon axial movement of said lower mandrel with respect to said housing, said pipe gripping means being slidably mounted in said housing and comprising a cylinder having axially spaced sets of gripping teeth, there being means on the interior of said upper mandrel to force one set of said teeth inwardly when said mandrel is moved with respect to said pipe gripping means, said axial movement being caused by rotary movement of the housing when the gripping means and upper mandrel are interlocked.

4. An outside pipe cutting tool comprising an outer housing, a pipe gripping means releasably interlocked with an upper mandrel, a lower mandrel mounted within said housing, cutter members pivoted to said housing and operable upon axial movement of said lower mandrel with respect to said housing, said axial movement being caused by rotary movement of the housing when the gripping means and upper mandrel are interlocked, the lower portion of said upper mandrel being split to provide fingers, said fingers being threaded upon their interior and exterior surfaces, the threads on the interior surface of the upper mandrel engaging threads on the exterior surface of said lower mandrel.

5. An outside pipe cutting tool comprising an outer housing, a pipe gripping means mounted within said housing, an upper mandrel and a lower mandrel mounted within said housing, said upper mandrel having means thereon to cause the gripping action of said gripping means, cutter members pivoted to said housing and operable upon axial movement of said lower mandrel with respect to said housing, the lower portion of said upper mandrel being split to provide fingers, said fingers being threaded upon their interior and exterior surfaces, the upper portion of said lower mandrel being threadedly engaged with said fingers, so that relative rotation of the upper and lower mandrel imparts said axial movement.

6. An outside pipe cutting tool comprising an outer housing, a pipe gripping means mounted within said housing, an upper mandrel and a lower mandrel mounted within said housing, cutter members pivoted to said housing and operable upon axial movement of said lower mandrel with respect to said housing means to impart said axial movement, said cutter members having buttons secured thereto, said buttons being provided with spaced webs, said webs engaging grooves in said lower mandrel.

7. An outside pipe cutting tool comprising an outer housing, a pipe gripping means mounted within said housing, an upper mandrel and a lower mandrel mounted within said housing, cutter members pivoted to said housing and operable upon axial movement of said lower mandrel with respect to said housing means to impart said axial movement, said cutter members having buttons secured thereto, said buttons being provided with spaced webs, said webs engaging grooves in said lower mandrel, said cutter members being provided with means to engage the pipe being cut upon completion of the cutting operation.

5 8. An outside pipe cutting tool comprising an outer housing, a pipe gripping means releasably interlocked with an upper mandrel, a lower mandrel mounted within said housing, said upper mandrel being connected to said lower mandrel by a releasable screw-threaded connection, cutter members pivoted to said housing and operable upon axial movement of said lower mandrel with respect to said housing, said lower mandrel having pipe engaging guides pivoted thereto whereby the cutter members are centered, said axial movement being caused by rotary movement of the housing when the gripping means and upper mandrel are interlocked.

10 20 25 9. An outside pipe cutting tool comprising an outer housing, a pipe gripping means mounted within said housing, an upper mandrel and a lower mandrel mounted within said housing, cutter members pivoted to said housing and operable upon axial movement of said lower mandrel with respect to said housing means to impart said axial movement, said lower mandrel having pipe engaging guides pivoted thereto whereby the cutter members are centered, said guides having lugs upon their exterior surfaces, which are normally seated in a depression in said housing.
